BATH SALTS

Philip Stoughton, New York, N. Y.

No Drawing. Application May 23, 1934, Serial
No. 727,168

8 Claims. (Cl. 167—86)

This invention relates to an improvement in bath salts and especially to a new bath salt having novel characteristics with respect to its color and the color that it imparts to the bath.

- 5 Bath salts are often colored but seldom impart any appreciable color to the water in which they are dissolved. One reason for this is that a considerable amount of coloring material is necessary to color the water and if such a quantity 10 is incorporated in the bath salt it becomes deeply colored and unattractive. Since the reasons for using bath salts are largely esthetic, anything, such as poor appearance, that detracts from the esthetic effect is, of necessity, studiously avoided.
- 15 Furthermore, the dye often imparts its color to the tub, towels, wash cloths and even the body of the bather, causing stains which utterly preclude its use.

The present invention has been devised to provide a new bath salt in which these difficulties are overcome. The new salt contains a coloring material which thoroughly colors the water in which the material is dissolved, but which does not color the bath salt, or else colors the bath salt a different color or shade from that imparted to the water. Thus in addition to obviating the difficulty of overcolored bath salts, the new salt provides a color in the bath which may be so different from the color of the salt itself as to cause 25 a very impressive surprise to the user. For example, the salt may be white and color of the bath pink, or the salt may be pink and color of the bath yellow or lavender.

In addition to the aforementioned advantages, 30 the new salt is also highly desirable because the colored bath water does not tend to stain the skin, towels, bath mats and the like. Using the preferred coloring material, the color actually disappears from the bath water that is left upon 35 the skin because of the skin's natural acidity.

There are several satisfactory methods by 40 which the new salt may be manufactured, a large group of coloring materials that may be used and a wide variation possible in the kind and quantity of other ingredients incorporated. However, one particular coloring material has been found especially well adapted to use and a formula and method of compounding devised to utilize this material to the best advantage. That specific 45 embodiment of the invention will, therefore, be described in detail both to furnish an example of the general principles involved and as a description of a specific product to the production of which this invention is directed.

50 The coloring material especially adapted to use

is an organic dye known as phenolphthalein. This material is usually sold as a white powder. When dissolved in an acid or neutral solution it is colorless, but in an alkaline solution it undergoes a structural change and colors the solution pink, the depth of the color depending upon the quantity present and the alkalinity of the solution.

5 Such a coloring material may conceivably be incorporated in an acid or neutral bath salt and remain colorless until dissolved in bath water that is alkaline, whereupon the salt will exhibit a pink color throughout the entire bath. However, it is ordinarily desirable to use alkaline bath salts and this may be done providing only that 10 the phenolphthalein and other ingredients are mixed in powdered or crystal form rather than dissolved and crystallized together.

In the preferred formula phenolphthalein, 15 sodium sesqui carbonate and perfume are used 20 in following proportions:

Sodium sesqui carbonate	lbs	10
Phenolphthalein	oz	1/2
Perfume		25

Another satisfactory formula is:

Sodium sesqui carbonate	lbs	9 1/2
Sodium carbonate	lb	1/2
Phenolphthalein	oz	3/8
Perfume		30

The ingredients of these formulas are mixed in a dry state so as to retain the white color of the phenolphthalein powder. Trisodium phosphate and other salts may be added to the product or 35 substituted for sodium sesqui carbonate. Sodium bicarbonate and the phenolphthalein may be dissolved and crystallized together, but if the more alkaline sodium carbonate is present only mixing produces a white bath salt since the 40 phenolphthalein will turn pink if placed in solution with the sodium carbonate. In addition to the ingredients mentioned, others may be added, for example, a small amount of a secondary coloring material acting to tint the salt. 45 Ordinarily such coloring material has no appreciable effect upon the color of the bath but it may modify the color imparted to the bath by the primary coloring material.

Other coloring materials having the ability to 50 become colored or change color when dissolved in the water of the bath may be used instead of phenolphthalein or in addition thereto. Methyl orange, phenol red, thymol blue, alazarin yellow and methyl violet are examples of such materi- 55

- als and many others may easily be found. Their use and the selection, combining and proportioning of materials which will produce the desired color and shade in the salt and in the bath 5 are within the scope of this invention. Furthermore, the use of the compositions herein described in swimming pools, fish bowls and other places where colored water may be desirable is contemplated by the invention.
- 10 The present application is a continuation in part of my copending application Serial Number 574,929, filed November 13, 1931.
- I claim:
1. An alkaline bath salt including a small 15 amount of phenolphthalein in its colorless state.
  2. An alkaline bath salt containing around $\frac{1}{2}$ ounce of phenolphthalein to 10 pounds of the other ingredients, said phenolphthalein being present in its colorless state.
  - 20 3. A bath salt of approximately the following formula:
Sodium sesqui carbonate_____lbs. 10
Phenolphthalein in its colorless state____oz. $\frac{1}{2}$
Perfume
  - 25 4. A bath salt of approximately the following formula:
Sodium sesqui carbonate_____lbs. 10
Sodium carbonate_____lb. $\frac{1}{2}$
Phenolphthalein in its colorless state____oz. $\frac{3}{4}$
  - 30 5. A bath salt including as one of its ingredi-

ents a coloring material of the type ordinarily known as chemical indicators, the said material being present in the bath salt in a state that will be changed by contact with an alkaline liquid so as to impart to the liquid a color different from 5 the original color, if any, of the coloring material in the bath salt.

6. A bath salt including as one of its ingredients a coloring material of the type ordinarily known as chemical indicators, the said 10 material being present in the bath salt in a state that will be changed by contact with an alkaline liquid so as to impart to the liquid a color different from the original color, if any, of the coloring material in bath salt and a second 15 coloring material for imparting a color to the composition itself.

7. A bath salt including as one of its ingredients a quantity of phenolphthalein, said phenolphthalein being present in its colorless 20 state in the bath salt whereby it will be changed by contact with an alkaline liquid to impart to the liquid a color different from that of the bath salt.

8. A bath salt including as one of its ingredients a coloring material of the type ordinarily known as chemical indicators, the said material being present in the bath salt in a colorless state 25 that will be changed by contact with an alkaline liquid to impart a color thereto.

PHILIP STOUGHTON.
